DRAFT AND BUFFING GEAR

John H. Link, Merion, Pa., assignor to W. H. Miner, Inc., Chicago, Ill., a corporation of Delaware

Application April 2, 1934, Serial No. 718,540

22 Claims. (Cl. 213—9)

This invention relates to improvements in draft and buffing gears especially adapted for use in connection with mine cars.

One object of the invention is to provide a simple and efficient combined draft and buffing gear which may be economically manufactured.

Another object of the invention is to provide a gear of the character described in the preceding paragraph including yieldingly resisted draft and buffing members and a pin for connecting the draft member to the usual coupling link, wherein the draft member is lever actuated and the pin is also used as the actuating lever means for the draft member, thus reducing the number of parts required to form the complete mechanism and greatly simplifying the construction of the combined gear.

Other objects of the invention will more clearly appear from the description and claims hereinafter following.

In the drawings, forming a part of this specification, Figure 1 is an end elevational view of a mine car, partly broken away, illustrating my improved combined draft and buffing gear in connection therewith, the gear being shown partly in front elevation and partly in vertical section. Figure 2 is a horizontal sectional view, corresponding substantially to the line 2—2 of Figure 1, showing the gear in part plan and part horizontal section. Figures 3 and 4 are vertical sectional views, corresponding respectively to the lines 3—3 and 4—4 of Figure 1, Figure 3 showing a certain pin in side elevation. Figure 5 is a view similar to Figure 3, but showing the combined gear detached from the car and illustrating the manner of assembling the parts of the gear. Figure 6 is a top plan view of the pin shown in Figure 3, illustrating the usual coupling link as applied to the pin, the link being also indicated, in dotted lines, in another position to make clear the method of attaching the link to the pin. Figure 7 is a view similar to Figure 3, partly broken away, illustrating a different embodiment of the invention. Figure 8 is a top plan view of the pin and coupling member shown in Figure 7. Figure 9 is a view similar to Figure 3, illustrating still another embodiment of the invention. Figure 10 is a top plan view of the pin and coupling member shown in Figure 9.

Referring first to the embodiment of the invention illustrated in Figures 1 to 6 inclusive, 10 indicates the vertical end wall of a mine car, and 11—11 the floor sections at opposite sides of the car. The floor is depressed at the central portion of the car, thereby presenting a down-

wardly offset bottom wall section 12. The section 12 has upstanding flanges 13—13 at opposite ends thereof which overlap depending flanges 14—14 on the sections 11—11, the flanges 13—13 and 14—14 together forming side walls of the depressed portion of the floor. As shown in Figures 1, 2, 3, and 4, the end wall 10 is provided with an outwardly extending, horizontal bottom flange 15 which is spaced above the section 12 of the floor. As most clearly shown in Figures 3 and 4, the section 12 of the floor projects outwardly beyond the end wall 10. A transversely extending channel member 16 is disposed between the projecting portion of the bottom wall 12 and the flange 15, said channel member being, in effect, 10 an end sill. The channel member 16 has the web thereof disposed vertically and the top and bottom flanges projecting outwardly, as clearly shown in Figures 3 and 4. The flanges of the channel member 16 abut the flange 15 and the 20 projecting portion of the bottom wall 12 of the floor, as shown in Figures 1, 3, and 4, and are secured thereto in any suitable manner, preferably by rivets, as shown. At the opposite ends the vertical web of the channel member 16 is provided with rearwardly extending flanges 17—17 which overlap the flanges 13—13 of the section 12. 25

In carrying out my invention, as shown in Figures 1 to 6 inclusive, I mount the parts of the gear between the flanges of the channel member 16, as clearly indicated in the drawings. My improved combined draft and buffing gear comprises broadly a buffing head A; a draft member B; combined supporting and guide brackets 35 C—C; two cushioning springs D—D; and a pivoted coupling pin E.

The buffing head A is in the form of a hollow casting having spaced horizontal top and bottom walls 18—18, spaced vertical side walls 40 19—19, and a transverse front wall 20. The front wall 20 presents an outer curved buffing surface, as clearly shown in Figure 2. The bottom wall 18 is provided with a central opening 21 adapted to accommodate the bottom end of the pin E. As clearly shown in Figures 3 and 4, the rear wall of said opening is provided with a curved bearing face 22 for a purpose hereinafter described. The top wall 18 of the buffing head A is provided with a central opening 23, which 50 is somewhat longer than the opening 21, as clearly shown in Figures 4 and 5. The opening 23 is of such a length as to permit the necessary swinging movement of the pin E to actuate the draft member during the draft action of the gear. 55

Near the opposite ends, the front wall 20 of the buffing head A is provided with interior spring seats 24 having central bosses 25, which serve to center the springs. The buffing head also has the top and bottom walls 18-18 thereof provided with vertically aligned openings 26-26, which serve to receive the retaining bolts by which the buffing head is connected to the end of the car.

The draft member B is in the form of a casting having a vertical transverse rear section 27 and a forwardly extending central yoke member 28 formed integral with said section 27. The section 27 has spring seats 29-29 at opposite sides thereof on which the inner ends of the springs D-D are seated. As clearly shown in Figures 1 and 2, the springs D-D are two in number and are disposed at opposite sides of the yoke section 28 of the draft member B. The front ends of the springs D-D engage the spring seats 24-24 of the buffing head A and are held in centered position by the bosses 25-25, which engage within the coils of the springs. The yoke section 28 of the draft member B is closed at both ends, as shown in Figures 2, 3 and 5, and is of the vertical section shown in Figures 3 and 5. The rear end portion of the yoke section 28 is provided with top and bottom walls 30-30, as clearly shown in Figures 3 and 5, thereby providing top and bottom openings 31-31 at the forward end thereof, which extend from one side wall to the other of the yoke. The transverse front end section of the yoke is thickened and has a rear face 32 of the vertical section shown in Figures 3 and 5 so as to provide the proper bearing surface for rocking engagement of the pin E therewith. The opposed side walls at the forward end of the yoke section 28 are provided with transversely aligned, interior, horizontal top and bottom ribs 33-34. As clearly shown in Figures 3 and 4, the ribs 33 are somewhat shorter than the ribs 34. As shown in Figures 2 and 3, the forward end of the yoke is normally spaced inwardly from the transverse front wall 20 of the buffing head A so as to permit of the necessary rearward movement of the buffing head during a buffing action of the gear. The inner end portion of the draft member B is arranged between the top and bottom flanges of the channel member 16 and is thus supported by the channel member.

The combined guide and supporting brackets C-C are disposed at opposite sides of the mechanism and serve to support and guide the buffing head A. Each bracket C is of L-shaped form in plan, as clearly shown in Figure 2. Each bracket C has a forwardly projecting guide arm 35 which extends into the buffing head A between the top and bottom walls 18-18 thereof. The arm 35 is hollow, as shown in Figure 2, having spaced vertical side walls, top and bottom walls, and a curved front end wall. The top and bottom walls are provided with vertically aligned guide slots 36-36 adapted to accommodate the guide bolt 37 for longitudinal sliding movement. Two guide bolts 37-37 are employed, the same being disposed at opposite sides of the buffing head A. Each guide bolt 37 extends through the aligned openings 26-26 of the buffing head and serves to hold the buffing head assembled with the other mechanism of the gear, secures the mechanism to the end of the car, and also limits the outward movement of the buffing head. Each supporting bracket C has the arm 35 thereof provided with laterally

outwardly extending top and bottom flanges at the rear end thereof by which the bracket is secured to the channel member 16. As shown in Figures 1 and 2, the flanges of the brackets C-C are preferably riveted to the top and bottom flanges of the channel member 16. As most clearly shown in Figure 1, the bolts 37-37 are headed at their upper ends and have their bottom ends threaded within the openings 26-26 of the bottom wall of the buffing head A.

The pivoted coupling pin E comprises a shank portion 38, which is headed at the upper end, as indicated at 39. The head 39 is of oblong shape, as clearly shown in Figures 1, 2, and 6. The pin E forms, in effect, a lever by which the draft member B is pulled outwardly during a draft action. The lower end of the pin is reduced in width, as clearly shown in Figures 3 and 5, thereby providing a shouldered portion 40 which engages the curved bearing face 22 of the bottom wall 18 of the buffing head A. The shoulder 40 is rounded so as to properly cooperate with the bearing face 22. As shown in Figures 3 and 5, there is a substantial clearance between the front edge of the lower end of the pin E and the front end wall of the opening 21 of the bottom wall of the buffing head A. Between the ends thereof, the shank 38 of the pin E is provided with laterally projecting aligned trunnions 41-41 which engage between the ribs 33-34 and 33-34 of the yoke section 28 of the draft member B so that vertical displacement of the pin is prevented when the parts of the gear have been operatively assembled. The springs D-D normally hold the parts in the position shown in Figure 3, thereby forcing the front wall of the yoke against the forward side of the pin E and holding the pin against the rear walls of the openings 21 and 23 of the bottom and top walls 18-18 of the buffing head A. As clearly shown in Figures 2, 3, and 4, the normal position of the buffing head is such that the bolts 37-37 engage the front end walls of the slots 36-36 of the brackets C-C and that the inner end of the head is spaced from the outer ends of the top and bottom flanges of the channel member 16 and the front end edge of the bottom section 12 of the floor.

The usual coupling link for connecting one car to another is attached to the upper end of the pin E, such a link being shown in Figure 6 and indicated therein by 42. The head 39 of the pin E is of such a width that it will pass through the opening of the link 42 when the head is in longitudinal alignment with said opening. However, the head is of such a length, as shown in Figure 6, that it will overlap the side arms of the link when the link is arranged in the full line position, as shown in said figure. In applying the link to the pin, the link is placed in the dotted line position, shown in Figure 6, immediately above and in alignment with the head 39. The link is thus slipped over the head until it is disposed below the latter and is then turned to the full line position, shown in Figure 6.

The pin E is assembled with the other parts of the mechanism before the buffing head A, yoke member B, and the parts cooperating therewith are attached to the end of the car. The manner of assembling the parts will be clear upon reference to Figure 5. With the springs in position between the buffing head A and the draft member B, and the buffing head telescoped over the front

end of the draft member, the parts are compressed so that the buffing head occupies the position shown in Figure 5, that is, with the front wall of the head engaging the front end of the yoke section 28 of the draft member B. The pin E is then applied by inserting the same through the top opening 22 of the buffing head A. The relative position of the buffing head A and the draft member B is, at this time, such that the trunnions 41-41 of the pin E will clear the upper ribs 33-33 of the side walls of the buffing head A, thereby permitting entrance of the trunnions 41-41 between the ribs 33-34 and 33-34 when the pressure is removed from the buffing head, permitting the parts to assume the position shown in Figure 3. In Figure 5, the dotted line position of the pin E illustrates the manner of moving the trunnions 41-41 of the pin E past the ribs 33-33.

The operation of my improved draft and buffing gear, as illustrated in Figures 1 to 6 inclusive, is as follows: When the buffing head A is moved inwardly toward the car, the springs D-D are directly compressed against the rear section 27 of the draft member B, the draft member, at this time, being held stationary by engagement with the vertical web of the channel member 16. Rearward movement of the buffing head will be limited by engagement with the front end edges of the flanges of the brackets C-C. When a pulling force is applied to the coupling link in draft, the upper end of the pin E, which in effect forms a lever, is moved outwardly away from the car, the lower end of the pin rocking on the bearing face 22 of the bottom wall 18 of the buffing head A. Inasmuch as the inward movement of the buffing head is resisted by the springs D-D, the lever action of the pin E will pull the yoke outwardly away from the end of the car, thereby compressing the springs D-D against the buffing head. During this action the buffing head A is held against outward movement by the bolts 37-37 which are, at this time, in engagement with the front end walls of the slots of the brackets C-C. Outward movement of the draft member with respect to the buffing head A will be limited by engagement of the front face of the shank section 38 of the pin E with the front edge of the slot 23 of the buffing head A.

Referring next to the embodiment of the invention illustrated in Figures 7 and 8, the structure of the buffing head, draft member, supporting brackets, and shock absorbing springs is substantially the same as that hereinbefore described in connection with Figures 1 to 6 inclusive. In Figure 7, the buffing head is indicated by F and the draft member by G. The opening in the bottom wall of the buffing head F is provided with a curved bearing face 122 on the rear wall thereof, in all respects similar to the bearing face 22, hereinbefore described. The structure of the coupling pin, as shown in Figures 7 and 8, differs from the coupling pin E. The coupling pin in Figure 7 is indicated by H and is of substantially cylindrical cross-section. The shank 65 of the pin H is provided with trunnions 141-141 at opposite sides thereof which are similar to the trunnions 41-41, hereinbefore described, and engage between ribs 133-134 and 133-134 on the buffing head A to prevent vertical displacement of the pin and hold the parts assembled. At the bottom end, the shank of the pin H is provided with an annular groove 140 which engages the bearing face 122 so that the pin, in addition to rocking on said bearing face, may have swiveling movement thereon about the

longitudinal axis of said pin. At the upper end, the pin H is provided with an eye member 150 adapted to receive a bolt 151, which serves to secure a clevis 152 thereto. The arms of the clevis are longitudinally slotted, as indicated at 153-153, to slidably receive the bolt 151, thereby permitting the necessary relative movement between these parts. The clevis 152 takes place of the usual coupling link, such as the link 42 shown in Figure 6.

The operation of the embodiment of the invention illustrated in Figures 7 and 8 is identical with that of the device shown in Figures 1 to 6 inclusive, with the exception that rotary swiveling movement of the pin H about its longitudinal axis is provided and that the connecting coupling element or clevis 152 is swingable about a horizontal axis.

Referring next to the embodiment of the invention, illustrated in Figures 9 and 10, the structure 20 of the device corresponds substantially to that shown in Figures 7 and 8, with the exception that the upper end of the structure of the lever acting coupling pin is somewhat modified and that a different form of connecting link is employed. 25 In Figure 9 the buffing head F and the draft member G correspond exactly to the members F and G shown in Figure 7. The coupling pin is indicated by K in Figures 9 and 10 and has the shank thereof formed precisely like the shank of 30 the pin H, the same being provided with the annular groove 140 at the lower end engaging the bearing shoulder 122 on the inner end wall of the opening in the bottom of the buffing head F, and trunnions 141-141 cooperating with ribs 133- 35 134 and 133-134 at opposite sides of the yoke section of the draft member G. At the upper end, the pin K is provided with an eye member 160 having the opening thereof rearwardly tapered, as clearly shown in Figure 9. The connecting 40 link element, as shown in Figures 9 and 10, has an elongated eye portion 161 and a cylindrical shank 162 extending from said eye portion. The shank 162 extends through the opening of the eye 160 and is headed at the outer end, as indicated at 45 163. The engaging portion of the head 163 and the eye portion 160 of the pin K are rounded so as to provide the proper swiveling action to permit angling of the connecting link member upward and downward with respect to the pin K. 50 As will be evident, the pin K has swiveling action about its vertical axis on the bearing face 122 in a manner similar to the swiveling action of the pin H, described in connection with Figures 7 and 8.

I have herein shown and described what I now consider the preferred manner of carrying out my invention, but the same is merely illustrative and I contemplate all changes and modifications that come within the scope of the claims appended hereto.

I claim:

1. In a combined draft and buffing gear for cars, the combination with a buffing head movable inwardly toward the end of the car; of an outwardly movable draft member; yielding means opposing relative movement of the buffing head and draft member; and lever means fulcrumed at its lower end on the buffing head, said lever means being operatively connected to the draft member for actuating the same.

2. In a combined draft and buffing gear for cars, the combination with a support; of a buffing head slidably mounted on said support; a yoke slidably mounted on said support, said head and yoke being relatively movable toward

and away from each other; means yieldingly resisting relative approach of said head and yoke; and an upright lever actuated in draft, said lever being pivoted to swing about its lower end and 5 having the mid-section thereof engaging the yoke to pull the same outwardly when the upper end of the lever is pulled outwardly away from the car in draft.

3. In a combined draft and buffing gear for 10 cars, the combination with a buffing head movable inwardly toward the end of the car; of a yoke movable outwardly away from the end of the car; means yieldingly opposing relative movement of the head and yoke; and a lever having 15 means at the upper end for connecting the same to a coupling link, said lever being pivoted at the lower end on the buffing head, and having bearing between its ends on the yoke.

4. In a combined draft and buffing gear for 20 cars, the combination with a buffing head movable inwardly toward the end of the car, said head having a forwardly facing bearing shoulder thereon; of a yoke movable outwardly away from the end of the car, said yoke having a rearwardly 25 facing bearing face thereon; means yieldingly resisting relative approach of the head and yoke; and a lever having means at its upper end for connecting the same to a coupling element, the forward side of said lever below said connecting 30 means having bearing engagement with the rearwardly facing bearing face of the yoke, and the rear side of said lever, below said point of bearing engagement with the yoke, bearing on the forwardly facing shoulder of said head.

35 5. In a combined draft and buffing gear for mine cars, the combination with a buffing head at the end of the car, supported for movement inwardly toward said end of the car; of a shock absorbing device opposing inward movement of 40 said head; a sliding yoke means for compressing said shock absorbing device against the buffing head in draft; and a lever having engagement with the yoke for pulling said yoke outwardly away from the end of the car, said lever having 45 means at one end thereof for connecting the same to a coupling element.

6. In combined draft and buffing gear for 50 mine cars, the combination with a buffing head at the end of the car, supported for movement inwardly toward said end of the car; of a shock absorbing device opposing inward movement of said head; a sliding yoke means for compressing said shock absorbing device against the buffing head in draft; and a lever for pulling said yoke 55 outwardly away from the end of the car, said lever being pivoted at one end to swing outwardly away from the end of the car and having the other end formed to receive a coupling link, said lever having the mid-section thereof in engagement with the yoke to actuate the latter in draft.

7. In a combined draft and buffing gear for 60 cars, the combination with a supporting structure fixed to the end of the car; of a buffing head 65 slidably carried by said supporting structure; shock absorbing means opposing inward movement of the buffing head; a lever bar having one end thereof provided with means for coupling the same to a coupling element of an adjacent car; and a yoke into which the lever extends, said yoke being actuated by said lever in draft, said yoke having a rear follower section engaging the rear end of said shock absorbing means to compress the same against the buffing head in 70 draft.

8. In a combined draft and buffing gear for 75 cars, the combination with a yoke member movable away from the end of the car in draft; of a shock absorbing means actuated by said yoke in draft; a buffing head movable inwardly toward the end of the car in buff and bearing on the outer end of said shock absorbing means; a vertical lever for actuating said yoke in draft, said lever having means at the upper end thereof for detachably receiving a coupling link; and 100 cooperating guide means on the yoke and lever for holding said lever against vertical displacement with respect to the yoke and buffing head when the parts are assembled.

9. In a combined draft and buffing gear for 105 cars, the combination with a buffing head movable inwardly toward the car; of a draft member movable outwardly away from the car; shock absorbing means opposing relative approach of said head and member; and a pivoted lever for 110 actuating said draft member to pull the same outwardly in draft, said lever being swiveled for rotary movement about its longitudinal axis and having means at one end thereof for detachably connecting the same to a coupling element. 25

10. In a combined draft and buffing gear for 115 cars, the combination with a buffing head movable inwardly toward the end of the car, said head having a forwardly facing bearing shoulder thereon; of a yoke movable outwardly away 120 from the end of the car, said yoke having a rearwardly facing bearing face thereon; yielding means resisting relative approach of the head and yoke; and a lever having swiveling movement on said shoulder about the longitudinal axis of 125 said lever, and also having rocking movement on said shoulder, said lever at another point bearing on said bearing face of the yoke, and at still another point having means thereon for attachment of a coupling element for connecting the 130 lever to an adjacent car.

11. In a combined draft and buffing gear for 135 cars, the combination with a buffing head movable inwardly toward the end of the car; of a draft member movable away from the end of the 140 car; means yieldingly opposing relative movement of said head and member toward each other; a pin having a head at one end and pivoted at the opposite end on said buffing head, said pin having pulling engagement with the draft 145 member, the head of said pin being elongated, said head being of a length greater and a width less than the opening between the side members of the usual coupling link.

12. In a combined draft and buffing gear for 150 cars, the combination with a buffing head movable inwardly toward the end of the car; of shock absorbing means opposing inward movement of 155 said head; a draft member bearing on the inner end of said shock absorbing means for compressing the same against the buffing head in draft, said draft member including a yoke section having a closed front end portion; and a pivoted pin having a head at the upper end adapted to engage over the usual coupling link, said pin being pivoted at the lower end and bearing between its ends on the inner side of said closed 160 front end section of the yoke.

13. In a combined draft and buffer gear for 165 cars, the combination with a buffing head movable inwardly toward the end of the car in buff; of an outwardly movable draft member having a vertical opening therethrough; yielding means compressible between said buffing head and draft member opposing relative movement thereof; and 170

an upright lever arm extending through said opening, said lever being pivoted at its lower end and having engagement, above the pivot thereof, with a wall of said opening of the draft member to pull the latter away from the end of the car.

5 14. In a combined draft and buffer gear for cars, the combination with a buffing head movable inwardly toward the end of the car; of a draft member movable outwardly away from the 10 end of the car, said draft member having a transverse front wall and a vertical opening in back of said wall; yielding means opposing relative movement of said head and member; and an upright lever fulcrumed at its lower end and swingable outwardly away from the end of the car in draft, said lever extending through the opening of said draft member and having engagement with said front wall to pull the draft member outwardly in draft.

15 15. In a combined draft and buffer gear for cars, the combination with a buffing head; of a sliding draft member having a pin-receiving opening; means yieldingly opposing relative approach of said head and member; a pin loosely 20 extending through said opening of the draft member and having engagement with a wall portion of said opening for actuating said draft member, said pin being pivoted at one end for swinging movement with respect to the draft member; 25 and means at the upper end of said pin adapted to receive a coupling connection.

30 16. In a combined draft and buffer gear for cars, the combination with a buffing head movable inwardly toward the end of the car; of a draft member movable outwardly away from the 35 end of the car, said draft member having a vertical opening therethrough; means yieldingly opposing relative approach of said head and member; an upright pin extending through said 40 opening of the draft member and having rocking engagement with a wall of said opening, said pin being pivoted at a point below said draft member for swinging movement with respect to said member; and a draft link swiveled to the 45 upper end of said pin for swinging said pin on its pivot outwardly against said wall of the opening of the draft member to move the latter outwardly away from the end of the car.

17. In a combined draft and buffing gear for 50 cars, the combination with a movable buffing head on the end of the car; of an elongated bar fulcrumed on one of its longitudinal side faces on said car for pivotal movement; a coupling link directly attached to and engaged with said bar 55 to swing said bar on its pivot outwardly away from the end of the car when a pulling force is applied to said link; and cushioning means engaged by the opposite longitudinal side face of said bar yieldingly opposing movement of said 60 buffing head and swinging movement of said bar.

18. In a draft device for a car, the combination with a pin pivotally supported on one of its longitudinal side faces at one end of said car; of a coupling link directly connected to and engaged with said pin for swinging said pin away from the end of the car when a pulling force is applied to said pin; cushioning means; and movable means engaged by the opposite longitudinal side face of said pin during swinging movement

thereof about its pivot for transmitting draft shocks to said cushioning means.

19. In a combined draft and buffing gear for cars, the combination with an inwardly movable buffing head on the end of the car; a sliding draft member on said end of the car; an abutment wall on said car against which the draft member bears to limit inward movement thereof; spring means interposed between said buffing head and draft member and opposing relative movement thereof; a pin swingingly mounted on the end of the car and engaging the draft member; and a coupling link directly connected to one end of said pin for swinging the same outwardly in draft to actuate said draft member.

15 20. In a combined draft and buffing gear for cars, the combination with a buffing head bodily movable inwardly toward the end of the car, said buffing head being held against outward movement in draft; of a draft element movable outwardly with respect to the buffing head and overlapping the latter; yielding means engaged respectively by said buffing head and draft element and yieldingly opposing inward movement of said buffing head and outward movement of the draft element; a coupling pin pivoted for swinging movement, said pin extending through the overlapped portions of said buffing head and draft element and having rocking engagement with the draft element to pull the same outwardly in 30 draft; and a coupling link directly connected to and engaged with one end of said pin for swinging said end of the pin away from the end of the car when a pulling force is applied to said link.

35 21. In a combined draft and buffing gear for cars, the combination with an outwardly movable draft member at the end of the car; of an inwardly movable buffing head telescoped over said draft member; means for limiting outward movement of said buffing head; means interposed between said buffing head and draft member yieldingly opposing relative movement thereof; a coupling pin extending through said buffing head and draft member, said pin being pivoted for swinging movement and engaging said draft member to actuate the latter; and a coupling link attached to and engaged over one end of said pin for swinging said end of the pin outwardly away from the end of the car when a pulling action is applied to said link, thereby forcing said draft member outwardly against said yielding means.

40 22. In a combined draft and buffing gear for cars, the combination with yielding means carried by the car for cushioning shocks; of means for transmitting shocks to said first named means including a buffing head, draft member, and a rocking coupling pin, said draft member and buffing head being telescopically engaged with 45 each other for relative longitudinal sliding movement, and said coupling pin extending through the telescoped portions of said member and head and bearing on said member to actuate the latter; and a coupling link directly attached to and engaged with said pin to swing the latter on its pivot when a pulling force is applied to said link.

50 JOHN H. LINK.
